UNITED STATES PATENT OFFICE

95,100

DESIGN FOR SHEET METAL

Harlan B. White, Bogalusa, La.

Application January 18, 1935, Serial No. 54,905

Term of patent 7 years

To all whom it may concern:

Be it known that I, Harlan B. White, a citizen of the United States, residing in Bogalusa, parish of Washington, State of Louisiana, have invented a new, original, and ornamental Design for Sheet Metal, shown in the accompanying drawing, in which

Figure 1 illustrates a portion of the sheet metal of my new design, and

Figure 2 is a sectional view, taken on the line 2—2 of Figure 1.

I claim:

The ornamental design for sheet metal, as shown.

HARLAN B. WHITE.
